UNITED STATES PATENT OFFICE.

STANLEY SMUTNY, OF CHICAGO, ILLINOIS, ASSIGNOR OF ONE-THIRD TO THOMAS CIKANEK, OF CHICAGO, ILLINOIS.

AUTOMOBILE SWITCH DEVICE.

Application filed February 1, 1923. Serial No. 616,248.

This invention relates to automobile switch devices, and has for its object the provision of a device of this character having contact making and breaking mechanism connected to the clutch and brake pedals of an automobile, and so arranged as to be independently operable by either of such pedals for establishing different circuits, and at the same time being so constructed that the simultaneous operation of such pedals causes the closing of only one of said circuits.

Other objects will appear hereinafter.

The invention consists in the combinations and arrangements of parts hereinafter described and claimed.

The invention will be best understood by reference to the accompanying drawings forming a part of this specification, and in which—

Fig. 1 is a fragmentary view of an automobile body, partly in section, showing my invention in position thereon;

Fig. 2 is an enlarged top plan view of a switch used in connection with my invention, showing same in neutral position in full lines, and in operative position in dotted lines;

Fig. 3 is a section on the line 3—3 of Fig. 2;

Fig. 4 is a front elevation of signalling lamps adapted to be operated by said switch; and

Fig. 5 is a diagrammatic layout of the various circuits used in connection with my invention.

The preferred construction illustrated in the drawings comprises a switch casing 10, preferably secured beneath the floorboard 11 of an automobile. Such casing is preferably provided with a disc 12 of suitable insulating material and secured in said disc at one side of the casing is an elongated contact member 13, preferably arcuate in shape, such contact member being connected by a wire 14 with a suitable source of current,

such as the battery 15 ordinarily mounted on the automobile. On the opposite side of the casing 10, mounted in the disc 12, are spaced contacts 16 and 17, the contact 17 being connected by a wire 18 to a lamp 19, which lamp is preferably grounded on the frame of the automobile, and provided with suitable indicia 20, in this particular instance the word

“Go.” The contact 16 is connected by means of a wire 21 with a lamp 22, which lamp is also grounded on the frame of the automobile, and preferably provided with suitable indicia 23, such as the word “Stop”. The lamps 19 and 22 are preferably disposed at the rear of the automobile, and preferably support another lamp 24, which is detachably mounted upon the lamps 19 and 22 by means of bent lugs 25, such lamp preferably being connected in series with a lamp 25 mounted on the dashboard of the automobile in the ordinary manner.

Secured to the casing 10 and projecting through the disc 12, is a stud 26, and rotatably mounted on said stud, preferably intermediate its ends, is a bar 27, the ends 28 of which preferably project outside of the casing 10, through slots 29, said ends being preferably turned as shown, and provided with perforations 30 and 31. The bar 27 is preferably mounted on a disc 32 of insulating material, and secured to the underside of the disc 32 is an elongated metallic plate 33, as shown, such plate being adapted to establish connections between the contacts 13, and the contacts 16 and 17, when the bar 27 is oscillated.

The means for oscillating the bar 27 comprises a connection between one end of such bar and the brake pedal 34 of the automobile, and a connection between the other end of the bar 27 and the clutch pedal 35. The

means for connecting the end of the bar 27 to the brake pedal preferably comprises a rod 36 pivotally secured to such brake pedal, the rear end of which projects through the aperture 30 in the bar 27, such rod preferably having a washer 37 and lock nuts 38, on its inner extremity, there preferably being being a spring 39 interposed between the washer 37 and the end of bar 27. The means for connecting the clutch pedal to the bar 27, preferably consists of a rod 39 similar to the rod 36, one end of the rod 39 being pivotally connected to the clutch pedal 35, and the opposite end of said rod projecting

through the aperture 31 in the end of the bar 27, the extremity of the rod 39 also being provided with a washer 40 and lock nuts 41, and there being a spring 42 of lighter and weaker construction than the spring 39, interposed between the washer 40 and the adjacent end of the bar 27.

By this arrangement in the normal position of the clutch and brake pedals, but one end

of the clutch and brake pedals, but one end

of the bar 27 is held continuously in contact with the arcuate contact member 13, while the other end of the bar is held between the contacts 16 and 17, in neutral position. 5 When the clutch pedal 35 is depressed the bar 27 is swung into position to engage the contact 17, and thus close the circuit through the lamp 19. When the brake pedal 34 is depressed the bar 27 is swung into position 10 to engage the contact 16 and close the circuit through the lamp 22. When both pedals are simultaneously depressed, due to the greater strength of the spring 39, the bar 27 is swung into position to engage the contact 16, and 15 thus establish a circuit through the light 22. The features above described are particularly desirable for the reason that oftentimes in order to slacken the speed of the vehicle preparatory to stopping, the driver cuts 20 the power to the minimum and depresses the brake pedal without depressing the clutch pedal, relying on the compression of the motor to aid in reducing the speed of the vehicle, the light 22, which may be red in 25 color, during this period being lighted signifying that the driver intends to stop, and finally when the clutch pedal is depressed, the red light remains in operation due to the fact that the spring 39 overcomes the 30 spring 42; and when both brake and clutch 35 pedals are depressed simultaneously, the red light is energized in like manner. It is also frequently desirable to reduce the speed of the vehicle by disengaging the clutch, with 40 no intention of stopping; consequently when the clutch pedal is separately depressed the green light will signify that no stop is to be made. This feature is also useful in starting the vehicle as it is apparent that the 45 green light is operated by depression of the clutch, thus signifying that the vehicle is about to proceed.

While I have illustrated and described the preferred form of construction for carrying 45 my invention into effect, this is capable of variation and modification without departing from the spirit of the invention. I, therefore, do not wish to be limited to the 50 precise details of construction set forth, but desire to avail myself of such variations and

modifications as come within the scope of the appended claims.

Having described my invention, what I claim as new and desire to secure by Letters Patent is:

1. An apparatus of the character described comprising a casing; a disc of insulating material mounted in said casing; an arcuate contact mounted in one side of said disc; a plurality of spaced contacts mounted in the other side of said disc; a swinging member having a disc of insulating material thereon, there being a metallic plate connected to said disc and adapted to connect said contacts by swinging movement of said swinging member; means for connecting the opposite ends of said swinging member to the clutch and brake pedals of an automobile; and resilient means disposed in said connecting means, one of which is of less strength than the other, so arranged that when both pedals are depressed said swinging member will be operated in a predetermined direction. 55

2. An apparatus of the character described comprising a casing; a disc of insulating material mounted in said casing; an arcuate contact mounted in one side of said disc; a plurality of spaced contacts mounted in the other side of said disc; a swinging member adapted to have a disc of insulating material mounted thereon, there being a metallic plate connected to said disc and adapted to connect said contacts by the swinging movement of said swinging member; a rod pivotally connected to the brake pedal of an automobile and extending through one end of said swinging member; resilient means disposed between the end of said swinging member and the extremity of said rod; and a rod pivotally connected to the clutch pedal of said automobile and extending through the end of said swinging member, there being resilient means mounted between the end of said swinging member and the extremity of said rod, such resilient means being of less strength than the resilient means first mentioned. 75

In testimony whereof I have signed my name to this specification.

STANLEY SMUTNY.
